(57) **CLAIM**

The ornamental design for an adjustable sand mold toy, as shown and described.

DESCRIPTION

FIG. 1 is a first perspective view of the adjustable sand mold toy showing my new design.

FIG. 2 is a top plan view of the adjustable sand mold toy.

FIG. 3 is a bottom plan view thereof.

FIG. 4 is a front elevational view thereof.

FIG. 5 is a rear elevational view thereof.

FIG. 6 is a left side elevational view thereof.

FIG. 7 is a right side elevational view thereof; and,

(Continued)

FIG. 8 is a perspective view showing the design in an alternate configuration.

1 Claim, 5 Drawing Sheets
